Primary Examiner — Philip S Hyder*Assistant Examiner* — Darlington Ly*(74) Attorney, Agent, or Firm* — Plumsea Law Group, LLC(57) **CLAIM**

The ornamental design for a grill for automobile, as shown and described.

DESCRIPTION

FIG. 1 is a perspective view from the front side of a grill for automobile.

FIG. 2 is a front elevation view thereof.

FIG. 3 is a top plan view thereof.

FIG. 4 is a right side elevation view thereof; and,

FIG. 5 is a left side elevation view thereof.

The broken lines shown in the drawings illustrate portions of the grill that form no part of claimed design.
